5 Claims. (CL 226—127)

Apparatus, called filling limiters, are already known which are adapted to stop the supply of a liquid to a tank when the level in the latter reaches a predetermined limit and which operate, at that instant, by means of a vacuum produced in a movable wall chamber by an ejector pump through which the liquid current flows.

It is known, in this connection, that the vacuum produced by an ejector pump is dependent on the velocity and, consequently, on the discharge rate of the liquid delivered.

On the other hand, in manipulating certain liquids, the velocity of flow has to be limited in order to avoid, either evaporation, or the formation of an undesirable emulsion. Furthermore, it is obvious that an ejector pump which is designed for a small output is not suitable for a much larger output, without running the risk of creating an objectionable fall of pressure.

Consequently, hitherto, for satisfactory operation, an apparatus of this type provided with a given ejector pump, could only be used for discharge rates between a predetermined minimum "d" and maximum D.

This involved the necessity, in order to meet all the requirements of industrial practice, of constructing a set of apparatus with gradually differing minimum and maximum discharge rates.

The present invention obviates this drawback inasmuch as it enables the interval between the minimum discharge rate "d" and the maximum D for a given apparatus to be extended, under such conditions that, theoretically, a single apparatus would be sufficient for usual industrial requirements and practically, only the concern of avoiding the use of too bulky an apparatus, in the case of a very small discharge rate, will lead to the construction of a plurality of apparatus instead of a single one.

For this purpose, in apparatus of the type referred to, that is to say provided with a valve for closing the supply of liquid, the closing of which is caused by a vacuum created by an ejector pump in a movable wall chamber when the liquid reaches a predetermined level, the invention consists in the combination of said ejector pump with another pipe which is connected to the liquid supply but which is closed, when inoperative, by a calibrated valve, in such a manner as constantly to give the ejector pump a sufficient discharge rate, under a predetermined pressure, to perform its function, and to allow the excess discharge to flow directly into the tank, through said pipe, when said pressure is reached or exceeded.

Under these conditions, in spite of the varia-

tions of the discharge rate between very wide limits, the limiting of the level will be ensured in the tank which is being filled. This arrangement therefore enables an apparatus to be constructed which has a very large output and which will nevertheless retain all its sensitivity for very small outputs.

By way of indication and with the sole object of giving an idea of the possibilities provided by the present invention, it may be stated that it is possible to construct on these bases a limiting apparatus that operates for outputs of between 10,000 and 150 litres per hour for example, whereas hitherto an ejector pump controlled apparatus designed for an output of 10,000 litres per hour could not operate when the output fell below 3,000 litres and an apparatus adapted to operate for a minimum output rate of 150 litres per hour could not be used for an output above 500 litres.

The accompanying drawings show, by way of example, three embodiments of the filling limiting apparatus according to the present invention.

Fig. 1 of said drawings is a longitudinal section of a first embodiment.

Fig. 2 is a longitudinal section of a second embodiment.

Fig. 3 is a partial section along III—III of Fig. 2.
Fig. 4 is a partial horizontal section along IV—IV of Fig. 2.

Fig. 5 illustrates a phase of the operation.

Fig. 6 shows a partial vertical section of a third embodiment.

In Fig. 1, 1 designates the main frame or body of the apparatus. In said frame is formed the seat 2 of the valve 3 for stopping the liquid current arriving through the nipple 1^a. Said valve, which is loaded by a spring 4, is normally kept open, against the action of said spring, by a locking device adapted to be released by the movement of a diaphragm 5 when a suitable vacuum is produced in a chamber 6 of which said diaphragm forms one of the walls.

This locking device is formed, for example, by a lever 7, pivoted at 8, against which the stem of the open valve abuts and which is held in this position by a lock proper 9 pivoted at 10. A spring blade 11 holds this lock engaged and, on the other hand, presses it at the same time against the end of a rod 12 which is adapted to receive the action of the diaphragm 5. A push button 13 enables, if desired, the diaphragm to be operated by hand in order to swing the lock 9 and thereby cause the valve 3 to close.

On the other hand, an external lever 14 secured to a rotary cam 15 enables the lever 7 to be lifted

so as to return the valve to the open position after each automatic operation of the limiting device.

The chamber 6 communicates with the suction orifice 16 of an ejector pump which comprises an injection nozzle 17 and a delivery nozzle 18 and is designed only to operate when the orifice of said delivery nozzle is immersed. The injection nozzle 17 constantly communicates with the liquid chamber 19 formed after the seat 2 of the valve 3. A small duct 20, which separately places the chamber 6 in communication with the atmosphere of the tank being filled, enables air to return into the chamber 6 in the event of the ejector pump producing an unexpected suction in said chamber, for example when an air pocket bursts at the outlet of the injection nozzle 17.

This system is, by construction, adapted to produce the closing of the valve 3 when the ejector pump, through which a current is flowing at a predetermined speed v , is immersed.

According to the invention, the ejector pump is combined with a pipe 21 which preferably has a much larger passage in cross-section, and which extends between the liquid chamber 19 and the tank to be filled, said pipe being closed, when inoperative, by a valve 22 which is loaded by a spring 23 in such a manner as only to open under a pressure equal to or greater than the pressure p corresponding to the velocity v for which the ejector pump is adapted to fulfil its function.

Under these conditions, the ejector pump has a priority of discharge with respect to the pipe 21 which opens to allow the excess discharge to flow towards the tank only when the pressure in the chamber 19 is greater than p . Consequently, the operation of the limiting device is ensured for all values of the discharge rate greater than that which corresponds to p , the upper limit of utilization of the apparatus depending only on the cross-section given to the pipe 21.

It is advantageous, as shown in the drawings, in order to avoid having to use an ejector pump of great length, to surround same and the pipe 21 with a cylindrical casing 24 which enables the filling level to be brought substantially to the level of the lower orifice 24^a of said casing. As soon as said orifice is closed by the rising liquid, the air in the casing is driven through said liquid by the jet issuing from the ejector pump. The liquid then rises almost instantly up to the lower orifice of the delivery nozzle 18 and the ejector pump sucks in the chamber 6 and causes the valve 3 to close. The rapidity of the operation is such that at this instant, the level in the tank has only risen a negligible amount above the plane of the orifice 24^a.

Said casing also enables the position of the apparatus to be ensured by guiding in the filling nipple of the tank to be filled. The insertion may be limited by an adjustable stop 25 which enables the filling level to be fixed by fixing the position of the orifice 24^a relatively to the tank.

As stated, it is possible, by means of the invention, to construct an apparatus which is adapted to operate for discharge rates varying for example from 150 to 10,000 litres per hour and which consequently meets most of the usual requirements. The upper limit of such an apparatus could, moreover, be raised above 10,000 litres per hour; but it will be understood that in that case the bulk of the apparatus would be such as to make its use illogical in the case

of discharge rates in the region of the lower limit.

In the embodiment of Figs. 2 to 4, the same reference numerals designate the same members. 5 The tube formed by the ejector pump 17-18^a and its extension 30 is in this case included in a cylindrical pipe 31, the remainder of the cross-section of which forms a pipe 21¹ which performs the function of the pipe 21 of Fig. 1. The ejector pump discharges into the tank through the orifice 32 provided in the casing 24¹ and communicating with the extension 30. The filling level is substantially on a level with the upper edge 5 of said orifice 32. The valve 22¹ for closing the 10 pipe 21¹ is in this case arranged in the lower part of said pipe which can discharge into the tank to be filled, when the valve is open, through the lateral orifices 34 of the casing 24¹. An adjustable stop, not shown, is mounted on the casing 24¹ as 15 in the case of Fig. 1.

As in the previous case, the suction orifice of the ejector pump communicates with the chamber 6 provided with a diaphragm 5.

The device for locking and releasing the valve 25 3 is in this case advantageously formed by a cam which is adapted to be operated rotatably from the outside and against which the stem of the valve abuts in the open position, said cam being connected to the diaphragm in such a manner as to move parallel with itself and allow said stem to escape, thereby to enable the valve to close when the vacuum causes the diaphragm to move.

The rod 35, which can be moved by the diaphragm 5, carries the cam 36, the position of 35 which behind the stem 3^a of the valve 3 is determined by the abutment of a shoulder 35^a against an inner wall of the frame. The extension 35^b of the rod 35 is engaged in a bore 37 of an operating key 38 which is adapted to drive 40 the cam by means of a projection 39 secured to said cam and engaged in another bore or recess 40 of the key. In Fig. 2, said projection, which is assumed to have been brought into the plane of the figure, has been drawn in chain dotted lines. 45 A spring 41 tends to hold the cam constantly in its above defined position, behind the stem of the valve.

On the key 38, outside the apparatus, is pinned a knob 42 provided with a ball 43 and with a spring 44 for resiliently engaging with a fixed cage 45 so as to form a mark for the user.

A spring 46 with flat convolutions, ensures fluid-tightness by pressing the key 38 against a gasket 47.

55 The device being in the position of Figs. 2 and 3, the valve 3 is open and its stem abuts against the cam 36. The ball 43 is engaged in the groove 45 of the cage 45.

It will be readily understood that when the 60 diaphragm moves towards the left of Fig. 2, responsive to the vacuum, it will also move the cam 36 towards the left by compressing the spring 41 and consequently said cam will allow the stem 3^a of the valve to escape, enabling the latter to close 65 by the action of the spring 4 (Fig. 5). At this instant, the cam will be held in its new position by the actual stem of the valve against which the projection of the cam abuts under the pressure of the spring 41.

70 For resetting the apparatus, that is to say for opening the valve 3 again, it suffices to operate the cam 36 rotatably by means of the knob 42. Starting from the position of Fig. 5, it will be understood that after a half-revolution, the projection 75 of the cam will have escaped from the stem of the

valve 3, and consequently the spring 41 will be able to move said cam in the axial direction and return it to the plane of the stem 3^a. Consequently, by continuing the rotation for a further half-revolution, the valve 3 will be lifted by the projection of the cam, and the engaging ball of the knob 42 will fall into the groove 45¹ and inform the operator that said valve is open.

In the embodiment of Fig. 6, the conduit formed by the ejector pump and the conduit controlled by the loaded valve are concentric.

The ejector pump 17²—18² is arranged in the axis of a tube 50 through which the liquid coming from the inlet chamber 19 flows down. Its suction orifice communicates with the vacuum chamber 6, for example through two series of small ducts 51 and 52, the first bored in radial arms 53^a of a tubular part 53 secured to the delivery nozzle 18², and the second in a sleeve 54 connecting the part 53 to the frame 1 of the apparatus.

In the part 53 are screwed a tube 30¹ which extends the ejector pump like the pipe 30 of Fig. 2, and a tube 21², concentric with the former, which performs the function of the pipe 21 of Fig. 1, or 21¹ of Fig. 2, and which at the same time acts as a guide for placing the apparatus in position on the tank to be filled. The seat of the valve 22² that controls the flow of the liquid through the pipe 21², is in this case formed as the lower end of the tube 50. The valve 22² is of annular shape and is adapted to slide without play on a tubular extension 55 of the injection nozzle 17². In its closed position it is flush with the liquid inlet orifice of said injection nozzle.

It will be understood that, without any other arrangement, the jet of liquid flowing from the large pipe 21² would be liable to isolate the central pipe 30¹ from the atmosphere of the tank and consequently, the ejector pump might operate prematurely.

In order to avoid this possibility, it suffices to set up a communication, through the annular jet of liquid falling from the pipe 21², between the pipe 30¹ and the atmosphere of the tank, for example by means of inverted gutters 56 fixed at the bottom of the tube 30¹ which is provided with registering recesses 57. The filling level will in this case be established substantially in the plane of the top of said recesses.

It is obvious that the invention is not limited to the embodiments described and illustrated and that it includes all the modifications of same based on the same principles.

I claim:

1. A filling apparatus for receptacles, which comprises a frame provided with a liquid inlet and with an outlet tube for allowing said liquid to flow into the receptacle to be filled, a valve for controlling the inlet of the liquid, said valve being subjected to the action of a spring which tends to keep it closed, a chamber provided with a movable wall, said wall being secured to a lock adapted to hold the stem of the valve in the open position when the wall is in its inoperative position, and to release said stem and allow the valve to close responsive to its spring when a vacuum of predetermined value, produced in said chamber, moves said wall, an ejector pump arranged in the frame and forming a first path whereby the liquid that has passed through the valve has a free access towards the outlet, said ejector pump being connected to the movable wall chamber and adapted to create in said chamber the said vacuum when the liquid which is flowing into the

receptacle reaches a given level, and a conduit formed in the frame after said valve and adapted to form a second path for the liquid towards the outlet, said conduit being normally closed by a valve which is loaded at such a value that the ejector pump is always traversed by a liquid current whereof the predetermined rate of flow and pressure are suitable for said ejector pump to perform its function, this second valve only opening when the liquid reaches and exceeds said pressure.

2. A filling apparatus for receptacles, which comprises a frame provided with a liquid inlet and with an outlet tube for allowing said liquid to flow into the receptacle to be filled, a valve for controlling the inlet of the liquid, said valve being subjected to the action of a spring which tends to keep it closed, a chamber provided with a movable wall, said wall being secured to a lock adapted to hold the stem of the valve in the open position when the wall is in its inoperative position, and to release said stem and allow the valve to close responsive to its spring when a vacuum of predetermined value, produced in said chamber, moves said wall, an ejector pump arranged in the frame and forming a first path whereby the liquid that has passed through the valve has a free access towards the outlet, said ejector pump being connected to the movable wall chamber and adapted to create in said chamber the said vacuum when the liquid which is flowing into the receptacle reaches a given level, a conduit formed in the frame after said valve and adapted to form a second path for the liquid towards the outlet, said conduit being normally closed by a valve which is loaded at such a value that the ejector pump is always traversed by a liquid current whereof the predetermined rate of flow and pressure are suitable for said ejector pump to perform its function, this second valve only opening when the liquid reaches and exceeds said pressure, and means for opening and closing the first valve at will.

3. A filling apparatus for receptacles, which comprises a frame provided with a liquid inlet and with an outlet tube for allowing said liquid to flow into the receptacle to be filled, a valve for controlling the inlet of the liquid, said valve being subjected to the action of a spring which tends to keep it closed, a chamber provided with a movable wall, a slideable rod adapted to be moved in one direction by the action of said wall and in the opposite direction by the action of a spring, a cam secured to said rod and forming an abutment for the stem of the valve in the open position when the movable wall is in its inoperative position, whereas it releases said stem and allows the valve to close when the wall is moved by the action of a vacuum of predetermined value produced in said chamber, an external knob connected to said cam for enabling same to be rotated at will, said cam being so shaped that when the valve is closed, the cam can return, responsive to the action of its spring, after a certain rotation, into the plane of the stem of the valve and return said stem to the open position of the valve by an additional rotation, an ejector pump arranged in the frame and forming a first path whereby the liquid that has passed through the valve has a free access towards the outlet, said ejector pump being connected to the movable wall chamber and adapted to create in said chamber the said vacuum when the liquid which is flowing into the receptacle reaches a given level, a conduit formed in

the frame after the said valve and adapted to form a second path for the liquid towards the outlet, said conduit being normally closed by a valve which is loaded at such a value that the ejector pump is always traversed by a liquid current whereof the predetermined rate of flow and pressure are suitable for said ejector pump to perform its function, this second valve only opening when the liquid reaches and exceeds said pressure.

4. A filling apparatus for receptacles comprising, a frame having a liquid inlet and an outlet tube for liquid to flow into the receptacle, a valve for controlling the inlet of liquid to the frame, a chamber having a movable wall, said wall being connected to said valve to control the closing of the valve when said wall moves in one direction under the influence of a vacuum of sufficient value applied thereto, an ejector pump in said frame forming a first path for liquid to pass through said frame to the receptacle, said frame having an opening connecting the ejector pump with said chamber to create a vacuum in said chamber when the liquid in the receptacle reaches a certain level, said frame having a second path of flow for liquid to pass from the inlet to the receptacle, a valve in said second path normally closed when not operating, said second path valve having resilient means pressing it to closed position and said resilient means being so calibrated as to ensure a sufficient flow through the ejector pump to operate the movable wall and to let surplus liquid flow directly to the receptacle

through said second path when the required flow through the ejector pump is reached or exceeded.

5. A filling apparatus for receptacles comprising, a frame having a liquid inlet and an outlet tube for liquid to flow into the receptacle, a valve for controlling the inlet of liquid to the frame, a chamber having a movable wall, said valve having a stem, a cam for engaging the 10 valve stem for locking said inlet valve in open position, said cam being operatively connected to said movable wall so as to move parallel therewith so as to allow said stem to pass and allow the valve to close when the vacuum in said chamber effects movement of the wall, an ejector pump in said frame forming a first path for liquid to pass through said frame to the receptacle, said frame having an opening connecting the ejector pump with said chamber to create a vacuum in said chamber when the liquid in the receptacle reaches a certain level, said frame having a second path of flow for liquid to pass from the inlet to the receptacle, a valve in said second path normally closed when not operating, 15 said second path valve having resilient means pressing it to closed position and said resilient means being so calibrated as to ensure a sufficient flow through the ejector pump to operate the movable wall and to let surplus liquid flow directly to the receptacle through said second path when the required flow through the ejector pump is reached or exceeded.

EMILE PIQUEREZ.
